UNITED STATES PATENT OFFICE.

HERBERT EDWARD ROOKE, OF RANEEGUNGE, INDIA.

COMBINED SLEEPER AND CHAIR FOR RAILWAYS.

SPECIFICATION forming part of Letters Patent No. 634,032, dated October 3, 1899.

Application filed May 21, 1898. Serial No. 681,376. (No model.)

To all whom it may concern:

Be it known that I, HERBERT EDWARD ROOKE, mining engineer, a British subject, residing at Raneegunge, in the Province of 5 Bengal, India, have invented certain new and useful Improvements in a Combined Sleeper and Chair for Railways, of which the following is a specification.

This invention relates to an improved cast-10 iron combined sleeper and chair for use in the systems of permanent way in which the rail is suspended in the jaws of the chair.

In the cast-iron combined sleeper and chair at present in use the movable jaw of the chair 15 is dropped vertically into place and rests between two projecting ribs on the upper surface of the base-plate of the sleeper and is secured in its place by a single cotter passed through the two side ribs, the movable jaw, 20 and the gage-tie, which holds the two sleepers together laterally. The defect in this arrangement is that if the cotter (tapering key) works loose from vibration, which it is liable to do, or if it is maliciously removed the 25 railment of a train is certain to occur, as the gage-tie and movable jaw being set free the sleeper is thrust outward, the movable jaw slips back, and the rail drops down out of place. Further, an excessive percentage of 30 breakages occur owing to insufficiency of stiffness in the base-plate. This improved sleeper is designed to remedy these defects (a) by stiffening the plate with extra ribs, (b) by the use of double coppers, (c) by fitting the loose 35 jaw from the side of the sleepers, and (d) by using fish-plates and bolts for securing it in its place.

In the drawings hereunto annexed and 40 which are to be read as part of this specification the same letters are used to indicate like parts in each figure.

Figure 1 is a central vertical transverse section of one form of my device. Fig. 2 is a section on line 2 2 of Figs. 1 and 4. Fig. 3 is 45 a side view from the left of Fig. 1, except that a rail is shown in position in the chair. Fig. 4 is a plan of Fig. 3. Fig. 5 is a plan of a modification, and Fig. 6 is a central vertical transverse section of said modification.

50 In this improved combined sleeper and chair, Figs. 1, 2, 3, and 4, A is the base-plate, which is stiffened on the under side by a cen-

tral longitudinal rib B and a slight beading C all around the edges and on the top by sloping diagonal ribs D and central projections E, integral with the base-plate, through which the gage-tie F passes, rib G being continuous on one side of the plate only, its central part G' projecting outward to strengthen it at that point. The opposite side G², which forms 55 the sloping footings of diagonal ribs D, has a break in it at G³ to allow of the insertion of movable jaw J from the side, the sloping footing G³ being an integral part of J. The fixed jaw H of the chair is cast on the plate A, and 60 the movable jaw J is slid into place from the open side of the sleeper and is held in position by gage-tie F and coppers K and K', and to prevent it tilting its sloping toe L is held down by a corresponding slope L' in the casting 65 in contact with it. The rail M is shown suspended in the jaws of the chair. In all cases the movable jaw is set on the inside between the rails, and on a straight run the wide copper is placed outside the rail and the 70 narrow copper on the inside; but on a curve their positions are reversed, so as to allow a 75 certain amount of looseness to gage.

In Figs. 5 and 6 a modification of the above is shown by the addition of a wrought-iron 80 fish-plate N, bolted to side ribs D by short bolts P, which completely shuts in the movable jaw J. At the same time as fish-plate N considerably stiffens the base-plate A the 85 under rib B may be dispensed with.

Other modifications that may be adopted are: (a) Where traffic is light, rib B may be dispensed with without using the fish-plate N; (b) ribs G and G' may be dispensed with and two (a pair) wrought fish-plates used, 90 and (c) the copper-keys K and K' may be dispensed with and bolts and nuts substituted therefor.

Having now described my invention, what I claim as new, and for which I desire to secure Letters Patent, is—

1. In a combined sleeper and chair, the combination of an oblong base-plate A, having beaded edges C, a central longitudinal rib B on its under side and on top diagonal ribs D, central projections E through which gage-tie passes, side ribs G and G' and fixed jaw H all cast in one piece; and having an opening on one side for insertion of movable

jaw J, cotters K and K' which secure gage-tie F and said movable jaw J in position, both jaws holding rail M suspended by its head substantially as set forth.

2. In a combined sleeper and chair, the combination of an oblong base-plate A with beaded edges C, diagonal ribs D on top, central projections E through which gage-tie F passes, side ribs G and G' and fixed jaw H all cast in one piece with an opening on one side for insertion of movable jaw J, cotters K and K' for securing gage-tie F and movable jaw in position for suspending rail M in the chair-jaws substantially as set forth.

3. In a combined sleeper and chair, the combination of an oblong base-plate A, diagonal ribs D, central projections E through which gage-tie F passes, ribs G and G' and fixed jaw H all cast in one piece and having an opening on one side for insertion of loose jaw J, cotters K and K' for securing gage-tie F and loose-jaw J and a fish-plate N bolted to ribs D substantially as described and illustrated.

4. In a combined sleeper and chair the combination of a base-plate, a central jaw H and projections E and E'', said parts being connected with the base-plate, a detachable jaw

J, the base-plate and movable jaw being so formed that the jaw can be inserted from the side and inside of the projection E'', parts E, H, J and E'' being perforated transversely, gage-tie F passing therethrough, said parts H, J, and F having also perforations at right angles to the perforations first mentioned, and fastening devices therein.

5. In a combined sleeper and chair the combination of a base-plate, a central jaw H and projections E said parts being integral with the base-plate, a detachable jaw J, the base-plate and movable jaw being so formed that the jaw can be inserted from the side, and inside of the projection E'', the fixed undercut edge L', and the movable jaw having an edge L fitting the same, parts E, H and J being perforated transversely, gage-tie F passing therethrough, said parts H, J and F having also perforations at right angles to the perforations first mentioned, and cotters K, K' therein.

Signed at Calcutta, in the Province of Bengal, British India, this 5th day of April, 1898.

HERBERT EDWARD ROOKE.
